THIEF AND FOOL-PROOF CLOSURE

John R. Boyd, Natchez, Miss.

Application November 22, 1934, Serial No. 754,347

5 Claims. (Cl. 220—86)

This invention relates to a thief and fool-proof closure for tanks and receptacles generally and particularly for the fuel tanks of self-propelled vehicles.

5 It is particularly designed to provide a novel means which will render it extremely difficult and practically impossible to remove or tamper with the supply of fuel.

Another object is to provide such a means which 10 will not require the use of a key or operation of mechanism other than the closure or cover itself.

The more specific objects and advantages will in part be pointed out and otherwise become apparent from a consideration of the description 15 following taken in connection with accompanying drawing illustrating an operative embodiment.

In said drawing:—

Figure 1 is a vertical sectional view showing 20 the invention applied, for example, to the filling neck or tube of a fuel tank;

Figure 2 is a view of the parts of Figure 1 taken at a right angle thereto with the open position of the parts suggested in dotted lines, and

25 Figure 3 is a horizontal sectional view taken on the line 3—3 of Figure 2.

Referring specifically to the drawing, 10 designates the filling tube, neck or the like of a tank or other receptacle 11, for example, the fuel tank 30 of an automobile or self-propelled vehicle, although the invention is capable of use in connection with receptacles generally.

Pivoted to the upper end of the neck 10 by means of a hinge 12 is a cover or cap 13. Said 35 cover or cap moves on a horizontal axis and in closed position may be latched through the medium of a resilient fastening element 14 carried by the cover or closure 13 and having a shoulder 15 adapted to hook under a lug 16 carried by 40 the neck.

Disposed within the neck are a plurality of rings 17 at different heights to each of which is pivoted or hinged on a horizontal axis at 18, a plate or baffle 19 which in closed position rests 45 on the respective rings. It will be noted that the hinges 18 are located on opposite sides of the neck.

A rod or link 20, diagonally disposed, is pivoted as at 21 to the closure 13 and at 22 to the baffle 50 plate 19 while a rod or link 23 is pivotally connected to the baffle plates 19 at 24.

As a result of the construction described, opening of the cover or closure 13 to the dotted line position suggested in Figure 2 will cause corresponding opening of the baffle plates 19 as also

suggested in dotted lines, due to the connection of the plates by means of the rods 20 and 23 or equivalent means. When the closure 13 is released, the weight of the baffle 19 and rods 20 and 23 will immediately and automatically close 5 the cover 13.

It will be apparent that when the cover 13 and the plates or baffles 19 are in the position shown in broken lines in Figure 2, that filling of the tank 11 may be accomplished, but that removal of the contents of the tank 11 by siphoning cannot be accomplished because of the staggered arrangement of the baffle plates 19 when in the dotted line position as stated.

Various changes may be resorted to provided 15 they fall within the spirit and scope of the invention.

I claim as my invention:—

1. In combination with the filling passage of a tank or the like, a cover for said passage, and 20 a plurality of baffle elements pivotally mounted within the passage and interconnected with each other and with said closure for opening movement through opening movement of said closure, the pivot means for the baffle elements being on 25 opposite sides of the passage.

2. In combination with the filling passage of a tank or the like, a plurality of baffle elements disposed at different elevations and pivotally mounted within the passage, the pivot means for 30 the baffle elements being on opposite sides of the passage, means connecting said elements together for simultaneous opening and closing, and a closure for said passage having a connection with one of said baffles whereby the baffles 35 will be opened and closed through the movement of said closure.

3. In combination with the filling passage of a tank or the like, a plurality of baffle elements disposed at different elevations within the passage, means connecting said elements together for simultaneous opening and closing, a closure for said passage having a connection with one of said baffles whereby the baffles will be opened and closed through the movement of said closure, rings within the passage, and means pivoting the baffles to said rings, the pivot means for the baffles being on opposite sides of the passage.

4. In combination with the filling passage of a tank or the like, a plurality of baffle elements disposed at different elevations within the passage, means connecting said elements together for simultaneous opening and closing, a closure for said passage having a connection with one of said baffles whereby the baffles will be opened 50

and closed through the movement of said closure, rings within the passage, and means pivoting the baffles to said rings on opposite sides of said passage.

5. In combination with a filling passage of a tank or the like, rings therein at different elevations, baffle plates normally seated on said rings, means pivotally connecting the baffle

plates to the respective rings and on opposite sides of the passage, linkage connecting one baffle plate to the other baffle plate, a cover for said passage pivotally connected thereto, and linkage pivotally connecting the uppermost baffle plate and said cover, the last mentioned linkage being normally disposed at an angle.

JOHN R. BOYD.
